FIRE EXTINGUISHER

Paul A. Stover and Louis B. Miller,
San Francisco, Calif.

Application May 14, 1934, Serial No. 725,530

3 Claims. (Cl. 169—26)

The present invention relates particularly to that type of fire extinguisher wherein a fire extinguishing liquid is released from a closed container through the action of an abnormally high temperature.

It is one object of the invention to provide a device of the character indicated so constructed and arranged as to obviate the necessity of providing the frangible container of the fire extinguishing liquid now so commonly in use.

It is another object of the invention to provide an automatically operated fire extinguisher that will be economical to manufacture, simple in form and construction, strong, durable, positive in operation, and highly efficient in its practical application.

In the drawing:

Figure 1 is a side elevation of a device embodying our invention in position and ready for use.

Figure 2 is a side elevation of the same in position for discharging.

Figure 3 is a section through the discharge end of one embodiment of the invention.

Figure 4 is a section through the discharge end of another embodiment of the invention.

Figure 5 is a section through the discharge end of still another embodiment of the invention.

Referring now more particularly to the drawing, we show at 1 a hollow cylinder made of tin or any other suitable material having a closed bottom end 2 and a top end 2 having holes 4 formed therein.

At 5 is a cap member of sufficient size to cover all of the holes 4, and this cap is soldered to top 3 with a fusible alloy that melts at a predetermined temperature. This cap is preferably bowed as at 6 and soldered completely around the edge at 7 in such a manner as to completely seal off the several apertures or holes from communication with the outside atmosphere. To the top of the cap 5 is secured a ring 8.

A bail 9 is mounted on the container 1 at points disposed below the center of gravity of the same as at 10—10, and this bail is passed through the ring 8 as at 11 some distance above the connection of the ring to the cap 5.

Assuming the container 1 to have been filled with a suitable fire extinguishing liquid such as carbon tetrachloride, or substantially filled to a point as 12, it is hung on a suitable overhead support 13 by means of a hook 14 engaging the ring 8. In this position the bail 9 is inoperative.

In the event of a fire the hot air circulating around the cap 5 heats the same and also the air pocketed beneath it, and melts the fusible

alloy at 7. When this occurs the weight of the filled receptacle causes it to drop so that the bail 9 seats upon and is supported by the ring 8 and thereby becomes operative to support the container 1. But since the bail is connected to the container below its center of gravity the container immediately overturns as shown in Figure 2 and its contents is discharged through the orifices 4.

If desired the container 1 may be refilled and the cap 5 replaced, after which the device is again ready for use.

In the embodiment of the invention shown in Figure 4 a laterally extending flange 15 is formed on the container 1 and a cap member 16 soldered thereto. In this embodiment the fusible alloy used as a solder is completely removed from the cold contents of the container, and the heated air circulates around both the flange and the edge of the cap so that the heat is carried to the solder from both sides.

In the embodiment shown in Figure 5 the holes 4 are themselves sealed with the fusible alloy and the alloy in certain of the holes is attached to the cap 17 as at 18. Since the cap is slightly spaced from the top 3 the heated air has access to and melts the alloy in the holes and thus permits discharge of the contents of the container.

A particular advantage of this invention is that the liquid in the container does not contact the fusible alloy and the sealing is so effected that it is subjected to the full effect of the currents of heated air generated by the fire. Furthermore where a frangible container is used the contents is discharged in a body, and if it is desired to secure rapid diffusion of the liquid some additional means must be provided, while the present invention permits inclusion of the diffusion means in the container itself.

Another advantage is that when the temperature of the room in which the unit is installed rises beyond a predetermined point the expansion of the vapor given off by the carbon tetrachloride forces the cap 5 off of the container the instant the fusible alloy softens, thermo-dynamically controlling the operating means of the entire unit.

It is to be understood, of course, that while we have herein shown and described but three embodiments of the invention, changes in form, construction, and method of assembly and operation, may be made within the scope of the appended claims.

We claim:

1. An automatic fire extinguisher comprising,

8 a container having discharge openings formed therein above its center of gravity, heat responsive sealing means for said openings having a hanger attached thereto, a bail pivotally connected to the container below its center of gravity and passing through said hanger in spaced relation to its point of attachment to the sealing means.

10 2. An automatic fire extinguisher comprising, a container having discharge openings formed therein above its center of gravity, heat responsive sealing means for said openings provided with a hanger, a member pivotally connected to the container below its center of gravity and extending upwardly to a point adjacent said hanger

5 but spaced therefrom and movable into engagement with the hanger to tip the container when the sealing means is released.

15 3. In a device of the character described, a container for fire extinguishing material having openings formed in one end thereof and having an outwardly directed flange associated therewith and encompassing the openings, and a closure seated upon the flange and disposed over the said openings and sealed to the flange with a fusible alloy disposed out of contact with the contents of the container but subject to the effect of heat through both the flange and closure.
